UNITED STATES PATENT OFFICE.

GEZA HORVATH, OF DETROIT, MICHIGAN.

METHOD OF MAKING ICE-CREAM CONTAINERS.

Application filed November 23, 1922. Serial No. 602,713.

To all whom it may concern:

Be it known that I, GEZA HORVATH, a citizen of the United States of America, residing at Detroit, in the county of Wayne 5 and State of Michigan, have invented certain new and useful Improvements in Methods of Making Ice-Cream Containers, of which the following is a specification, reference being had therein to the accompanying drawings.

This invention relates to ice cream containers and has special reference to that class of receptacles made of metal and in which ice cream or other matter may be 15 placed or packed.

My invention aims to provide a strong, durable and inexpensive metallic container having reinforced or strengthened upper and lower ends which are made without the 20 use of lead solder liable to contaminate the contents of a receptacle having parts secured together and joints filled by such a connecting or filling medium as lead solder. I obviate the necessity of using solder by resorting to spot welding, where necessary, and connecting the parts in a manner insuring 25 seams or joints that can be readily filled and covered when the interior of the container is tinned or provided with a suitable 30 interior surface or finish, such tending to make the container sanitary in all respects.

My invention further aims to provide the upper open end or mouth of the container with a protecting rim or chime, in the form 35 of a top ring providing an exterior laterally extending bead by which the container may be manually lifted and by which the container may be prevented from having its side walls injured by adjacent containers.

My invention further aims to provide a container having a lower closed end formed by a bottom piece and ring, the ring being secured within the lower end of the container body. This is accomplished by subjecting the bottom piece to internal pressure causing a wall of the bottom piece and the 45 wall of the container body to be bulged so that the bottom piece is anchored within the container body. Such a constructive arrangement of parts forms the bottom piece as a continuation of walls of a container body and when the interior of the body is 50 tinned or otherwise finished the bottom piece

of the container appears as though integral with the container body. 55

Reference will now be had to the drawing, wherein—

Figure 1 is a side elevation of the container, partly broken away and partly in section; 60

Fig. 2 is an enlarged cross sectional view of the top ring or chime of the container;

Fig. 3 is a similar view of the bottom ring and bottom piece of the container before the bottom piece is anchored relative to the container body; 65

Fig. 4 is a similar view after the bottom piece has been anchored in the container body;

Fig. 5 is a similar view illustrating an exterior bottom ring that may be used in lieu of an interior bottom ring; 70

Fig. 6 is an enlarged cross sectional view of a modified form of bottom piece before being anchored in the container body, and 75

Fig. 7 is a similar view showing the bottom piece fixed in the container body.

To put my invention into practice, I provide a cylindrical body or shell 1 preferably made from a piece of metal rolled or otherwise brought to cylindrical form with a single longitudinal seam or joint that may be spot welded or the ends of the strip of metal otherwise secured together to form a strong and durable container body having an upper annular wall 2 and a lower annular wall 3. 80

Mounted on the upper annular wall 2 is a top ring 4 formed with an annular interior seat 5, an annular exterior bead or rib 6, 90 and a chime or rim 7. This top ring may be made from a strip of metal rolled to provide the cross sectional shape shown in Fig. 2 and then rolled or otherwise brought to ring form with the ends of the strip of metal connected by a scarf joint welded or otherwise formed. The seat 5 permits of the top ring being seated on the upper edge of the wall 2 with approximately the lower half of the top ring surrounding the wall 2. The inner surface of the wall 2 will be flush with the inner wall of the chime or rim 7 and said top ring may be spot welded or otherwise secured to the wall 2 of the container body or shell 1. The bead or rib 6 affords an 95 annular reinforcement and hand grip at the

lower edge of the top ring and at such a point as to prevent an adjacent container or receptacle, on the same level, contacting with the container body or shell.

5   Mounted in the lower end of the container body or shell 1 against the wall 3 is an interior bottom ring 8 having a flat bottom wall 9 flush with the lower edge of the wall 3. The top wall of the bottom ring 8 is 10 provided with an annular concave seat 10 terminating in a feather edge at the wall 3 and this bottom ring may be made from a strip of metal having a cross sectional shape as shown in Fig. 3 with the strip of metal 15 rolled or brought to ring form with the ends of the strip of metal welded or otherwise connected, for instance by a spark or lapped joint.

Thus far I have provided a container body or shell with an interior bottom ring, and in order to provide the container with a bottom a method is involved in connection with a sectional, take-apart mold, holder or other annular knock-down member 11 provided 25 with an annular forming groove 12. To form the bottom of the container I provide a cupped or dished bottom piece 13 having an annular wall 14 with its upper edge beveled, as at 15. This bottom piece is placed 30 in the container body 1, on the bottom ring 8, and the peripheral bottom edge of said bottom piece conforms in curvature to the seat 10 of the bottom ring 8, with the annular wall 14 in parallelism with the wall 3, 35 as best shown in Fig. 3. The bottom piece 13 can be placed in the container body 1 before or after the container body is placed in the mold 11. The forming groove 12 of the mold is opposite the walls 14 and 3 and as 40 though the wall of the groove 12 was a continuation of the seat 10 of the bottom ring 8. With these parts so located the wall 14 is subjected to an internal pressure by a reamer or other instrumentality which will 45 forcibly expand or distend the walls 14 and 3 into the forming groove 12, causing the wall 3 to be bulged in the formation of an exterior annular bead and the wall 14 to be seated in such bead with its beveled edge 15 50 flush with the wall 3 thus placing the wall 14 as a continuation of the wall 3. This is best shown in Fig. 4 where the bottom piece 13 assumes a position causing it to be anchored relative to the container body, and it 55 will be noted that the beveled edge 15 of the wall 14 meets the wall 3 by a line connection, almost invisible in a full sized container and consequently this connection may be absolutely closed when the interior of the container 60 is tinned or provided with a suitable interior finish. Since there is an intimate contacting relation between the walls 3 and 14, brought about by pressure, no space or air gap can exist and if for some reason or 65 other such a space or gap did exist it would

be filled during the tinning of the interior walls of the container.

I may resort to spot welding but aside from this it will be noted that the bottom piece 13 cannot become vertically or laterally displaced, and that the connection between the bottom piece 13 and the lower portion of the wall 3 is closed and reinforced by the bottom ring 8 providing a substantial bottom support for the body of the container.

The same means of subjecting the bottom piece 3 to internal pressure may be used at the upper end of the container for expanding or pressing the wall 2 on to the seat 5 in which case a mold 16 will be placed about the top ring as a backing for such ring during the expanding or seating of the wall 2.

Instead of the interior bottom ring 8 I may use an exterior bottom ring or band 17 which is sandwiched between the mold 11 and the wall 3 so that when the walls 3 and 14 are expanded or distended the exterior ring will also be expanded or distended into the forming groove 12 and thus become anchored about the lower end of the container body, providing a three-ply thickness at the periphery of the bottom piece 13 and a two-ply thickness below said bottom piece. Spot welding may also be resorted to as a means of positively connecting the exterior bottom ring 17 to the wall 3.

As shown in Figs. 6 and 7 the holder 11 may have a forming groove 18 of a different cross sectional shape or contour from the groove 12 and the wall 14 of the bottom piece 13 has a beveled edge 19 the reverse of the beveled edge 15. In consequence of the groove contour of the holder 11 the walls 14 and 3 can be pressed into the groove 18 until the wall 14 is flush with the container body 1, thus eliminating the curving or bulging of the wall 14 as shown in Figs. 4, 5 and 6.

In practice, the parts of the container or receptacle are tinned before being assembled, especially those parts which are placed in intimate relation to form a joint or seam. It is therefore obvious that when the interior of the container or receptacle is tinned that such tinning operation practically renders the container or receptacle an integral or homogenous structure. This is particularly true where seams or tight joints are welded throughout, in contradistinction to spot welding, and such thorough welding is resorted to wherever it is necessary to add strength and rigidity to parts of the container or receptacle that will be subjected to abuse.

The methodical steps that may be used in the production of the container or like receptacle have been brought out in the appended claims, and while in the drawing there are illustrated the preferred embodiments of my invention, it is to be understood

that the construction and manner of assembling the parts are susceptible to such changes as are permissible by said claim.

What I claim is:—

- 5 A method of making a container consisting in placing a body in a mold having a groove with the body covering the mold groove, placing a bottom ring in said body with the lower edge of the bottom ring flush 10 with the lower edge of the body and an upper curved edge of the bottom ring terminating in substantially the plane of the lower edge of the mold groove, placing a bottom

piece in said body on said bottom ring with an annular wall of said bottom piece parallel 15 with that portion of said body covering the mold groove, and then forcing said body and the annular wall of said bottom piece outwardly at the groove of said mold to cause said body and bottom piece to conform in 20 curvature to approximately the curvature of the mold groove and the upper edge of said bottom ring.

In testimony whereof I affix my signature.

GEZA HORVATH.
